UNITED STATES PATENT OFFICE.

ROBERT E. FORRESTER, OF BURLESON, TEXAS.

CULTIVATOR-CUFF.

1,154,180.

Specification of Letters Patent.

Patented Sept. 21, 1915.

Application filed September 14, 1911. Serial No. 649,389.

To all whom it may concern:

Be it known that I, ROBERT E. FORRESTER, a citizen of the United States, residing at Burleson, in the county of Tarrant and State 5 of Texas, have invented a new and useful Cultivator-Cuff, of which the following is a specification.

The present invention is directed to improvements in connections for cultivator 10 beams, and has for its object to so construct a device of this character that the distance between the shovel standard and the beam may be regulated and adjusted, and held in 15 position independently and without molesting the angle or fastenings which control the angle of the shovel standard.

A further object of the invention is to produce a connection of this type constructed in such a manner that the shovel stand- 20 ard may be adjusted at different angles in relation to the beam.

With these and other objects in view, this invention resides in the novel features of construction, formations, combinations and 25 arrangements of parts to be hereinafter more fully described, claimed and illustrated in the accompanying drawing, in which:—

Figure 1 is a fragmentary side elevation 30 of a cultivator beam showing the device in place thereon. Fig. 2 is a similar view taken from the opposite side of the beam. Fig. 3 is a top plan view. Fig. 4 is a sectional view on line 4—4 of Fig. 3. Fig. 5 is a similar view on line 5—5 of Fig. 3. Fig. 6 is a bottom plan view.

Referring to the drawing, the numeral 1 designates a portion of a cultivator beam, and upon which the connection is mounted. 40 The connection 2 consists of a metal clamp comprising upper and lower jaws 3 and 4, respectively, the opposing faces of which are provided with semi-circular grooves for receiving the beam 1. Jaws 3 and 4 are integrally connected at one of their edges, and are spaced apart slight at their other edges by a slit 5.

The free edges of the jaws 3 and 4 are provided with registered perforations 6, in 50 which is engaged a clamping bolt 7 which serves to hold said jaws in their clamped adjusted positions upon the beam 1, as clearly shown in Figs. 3 and 4.

The connected edges of the jaws 3 and 4 are provided with a pair of spaced perfora- 55 tions 8 through which are passed the arms 9 of the U-bolt 10, the upper ends of said arms being threaded for engagement by the nuts 11 which are adapted to hold the bight portion of the U-bolt in tight engagement 60 with the sleeve 12. This sleeve 12, as will be clearly seen by reference to Figs. 2 and 5 of the drawing, rests in the semi-circular recess or groove 13 formed in the under face of the lower jaw 4. It will further be noted 65 that the purpose of the U-shaped clamping plate 10 is to hold this sleeve in engagement with the lower jaw of the clamping member or connection 2 so that the sleeve may be readily and quickly adjusted relative to the 70 jaw 4, solely by means of this U-shaped plate and consequently independently of any other adjusting member or connection, thus in loosening, adjusting and again tightening the sleeve, it is only necessary to use this 75 U-shaped bolt.

The shovel standard 17 is fastened to the sleeve 12 by any convenient method which holds said shovel standard at a proper angle, a well known form of connection being con- 80ventionally shown in the drawing.

The sleeve 12 and shovel standard 17 form no part of the present invention.

Extending outwardly from the connected edges of the jaw 4 is a curved flange 20 85 which engages a portion of the sleeve 12, thus aiding in embracing the same.

From this construction it will be seen that a connection of this type has been provided which will permit the shovel standard to be 90 adjusted longitudinally of the beam or at different angles thereto, also the distance between the beam and shovel standard may be varied independently of, and without disturbing any other adjustment. 95

What is claimed is:—

A clamp for cylindrical beams and the like comprising a body portion constituting two jaws which are formed integral at one side, said jaws having semi-circular grooves 100 formed in their confronting faces for receiving the beam, said clamp having a U-shaped clamping bolt extending through the integral portions of the jaws, said clamping bolt having a bight portion adapted to engage a member lying in a recess in one of 105

the jaws to hold said member in engagement with such jaw, whereby said member may be adjusted relatively to said recessed jaw independently of any other adjustment, 5 the free portions of said jaws having registering apertures therein, and a clamping bolt extending through said apertures

and serving to clamp the jaws securely on the beam.

ROBERT E. FORRESTER.
